UNITED STATES PATENT OFFICE.

SAMUEL P. SCOTT, OF HILLSBOROUGH, OHIO, ASSIGNOR TO THE STAR MANUFACTURING COMPANY, OF SAME PLACE.

CARRIAGE-CURTAIN FASTENING.

SPECIFICATION forming part of Letters Patent No. 409,069, dated August 13, 1889.

Application filed April 4, 1889. Serial No. 305,918. (No model.)

To all whom it may concern:

Be it known that I, SAMUEL P. SCOTT, of Hillsborough, in the county of Highland and State of Ohio, have invented certain new and useful Improvements in Carriage - Curtain Fastenings; and I do hereby declare that the following is a full, clear, and exact description thereof, reference being had to the accompanying drawings, and to the letters of reference marked thereon, which form part of this specification, in which—

Figure 1 is a side view of one of my improved carriage-curtain fastenings; Fig. 2, a vertical sectional view of the same; Fig. 3, a top view showing the head adjusted in dotted lines. Figs. 4 and 5 are detail views of the locking-pin head enlarged. Fig. 6 is an end view of the head C.

This invention is a carriage-curtain-fastening device; and it is an improvement upon the fastener shown in my patent, No. 401,720, of April 16, 1889.

The improvement consists, essentially, in a novel construction of the locking-pin, whereby the locking-grooves of the adjustable head and the locking ears or lugs on said pin are covered and protected, and catching of the curtain upon the head or outer end of the pin, as sometimes happens in the construction shown in my patent above referred to, is obviated; and this improvement will be clearly understood from the following description, taken in connection with the drawings.

A designates a base-piece having a central bore *a*, enlarged, as at B, and having a flange *b* surrounding the mouth of the enlarged portion of the bore.

C designates an adjustable head-piece, also having a central bore *c*, enlarged at its inner end, as at *d*, and adapted to receive the flange *b* of base B when the parts are fitted together. The outer face of head C is rounded, as shown, and at the outer end of bore *c* are formed pairs of diametrically-opposite notches D E, the opposite notches lying in lines at right angles to each other.

G designates a pin passing centrally through the base and head in the bores thereof, and this pin is secured to the base and loosely secured the head thereto. A coiled spring F is

placed on said pin between the head and base, being inclosed in the enlargements of the bores therein.

These parts are thus far constructed and arranged as described in my said patent. The outer end of pin G, however, is formed with an enlarged flattened head H, of such diameter that it will cover the notches D E in the head C, as shown, the extremity of said head being flattened, as shown in Figs. 2 and 6, to fit neatly against the flat inner face of the pin-head, and on the under surface of this head and at points diametrically opposite each other through the pin are made depending ribs *g*, which are small enough to enter the notches D or E when the head is properly turned, and allow head H to lie close against the rounded surface of head C.

In the patent above referred to it was found in practical working of the invention that the ears on the pin were liable to be caught and broken off by the curtain, or would tear the latter and injure the fingers of persons trying to button the curtain. To overcome these objections, the present construction of pin was invented, and by making the enlarged head H the ribs *g g* are not only prevented from catching the curtain, but are strengthened. The looks of the button are improved thereby, and, further, in the former patent the rain and dirt could collect in the notches in the head as the latter were unprotected, and hence the working parts of the button were liable to become clogged; but the head H prevents entrance of rain or grit into said notches and the life of the button is prolonged.

I do not claim herein, broadly, the parts shown and described in my aforesaid application, but only the improvements thereon, as above set forth.

The collar *b* is of less depth than the bore in head C, so that the latter can be pushed inward toward the base sufficiently to disengage its notches from the pin and permit it to be turned. The curtain is provided with ordinary button-holes and protectors, as indicated in the drawings.

Having thus described my invention, what I claim as new is—

In a carriage-curtain fastening, the combi-

nation of the stationary base A, the hollow head B, having a central bore and a rounded end flattened at the outer extremity of said bore and provided with diametrically-opposite pairs of notches D and E, and the spring F, with the stationary pin G, passing through both base and head and having a pair of diametrically-opposite ribs *g g* at its outer end, and an enlarged rounded head H, projecting beyond said ribs and fitting closely on the flattened end of the head and adapted to

cover the notches therein and strengthen the ribs, all substantially as and for the purpose specified.

In testimony that I claim the foregoing as my own I affix my signature in presence of two witnesses.

SAMUEL P. SCOTT.
